UNITED STATES PATENT OFFICE.

FRANK E. CARLSON, OF CHICAGO, ILLINOIS.

DESIGN FOR A FLOWER-STAND.

44,915.

Specification for Design.

Patented Nov. 25, 1913.

Application filed September 18, 1912. Serial No. 721,104. Term of patent 3½ years.

To all whom it may concern:

Be it known that I, FRANK E. CARLSON, a subject of the King of Sweden, residing at Chicago, in the county of Cook and State of Illinois, have invented a new, original, and ornamental Design for Flower-Stands, of which the following is a specification, reference being had to the accompanying drawing, forming part thereof.

Figure 1 is a front elevation of a flower

stand, showing my new design. Fig. 2 is a plan of the top of the same.

I claim:

The ornamental design for a flower stand, as shown.

FRANK E. CARLSON.
